UNITED STATES PATENT OFFICE

GUSTAV G. SCHLAM, OF NEW YORK, N. Y.

MEANS OF UTILIZING THE FORCED DRAFT OF THE PROPELLERS OF AEROPLANES

Application filed August 27, 1929. Serial No. 388,764.

My invention relates to aeroplanes and pneumatic motors at large; but the particular object of my invention is to accelerate the airship as now known by the application of an appliance for retaining and compounding the forced draft of the propeller. It is a further object of my invention to supply a means for minimizing the weight of the said airship by a retention of the forced draft of the propeller in such manner that it will buoy up said airship.

I have observed that in aeroplanes as now constructed the maximum pull force available from the propeller has not been obtained: that much of the forced draft of the propeller is lost. Therefore, it has been my plan to salvage the negative exhaust and put this draft to work both in accelerating and buoying up the airship.

I believe and I know that if the forced draft of the propeller might be trained to form two opposing volute forms backward and parallel to the course of the airship, that the speed of the airship would not only be enhanced, but the equilibrium of said ship would be predetermined; and if the forced draft of the propeller might be trained to form two opposing volute forms upward and parallel, perpendicular to the flying plane of the airship, the force of gravitation would be minimized and the said ship would be stabilized. My invention provides for a cone-like or other suitably shaped shield for the retention of the after draft of the propeller; and two opposing volute-like coil tubes for the carriage of the draft, to be set in a horizontal plane for the acceleration of the aeroplane and in a vertical plane for the buoyancy thereof. I maintain a vortex within these tubes; and through my control of the amount of the forced draft of the propeller permitted to enter the said shield, I may, in the one case, regulate the speed of the aeroplane, and in the other case, regulate the buoyancy of said plane.

It is manifest that if I may utilize the forced draft of the propeller as is for the acceleration of the aeroplane, and whereas this draft has heretofore been going to waste, I will be able to attain, through my

invention, present speeds with motors of less horse power and with less use of fuel.

Of my invention the following is a true and detailed specification, reference throughout being had to the accompanying drawings, the same numbers and letters thereon indicating the same features and parts thereof, wherever they occur.

Fig. 1 is a lateral elevation of arbitrary seaplane, showing the general assembly of the parts of my invention mounted upon the topmost part of the motor; one of the coiled pipes, that on the left side, being illustrated clearly here.

Fig. 2 is a plan view of the general assembly of the parts of my invention mounted upon the topmost part of the motor, seen from directly above, showing most clearly my shield and both of the coiled tubes.

Fig. 3 is a diagrammatic illustration of the path of the forced draft of the propeller throughout my contrivance for the acceleration of the aeroplane.

Fig. 4 is a detail of the safety exhaust described in detail later.

Fig. 5 is a sectional view of the mouth of the safety exhaust illustrating its construction and the manner of its working.

Fig. 6 is a sectional view of the valve controlling the return of the forced draft after its primary travel through the vortex.

Fig. 7 is a detail of the construction of the primary safety valve for the interference which may lessen the impact of the after draft of the propeller.

As it is the purpose of my invention to collect and reutilize the forced draft from the propeller of an aeroplane, I have provided a cone-like or other suitably shaped shield 1, as seen in Figs. 1 and 2, which surrounds slightly more than 180 degrees of the top half of the motor cycle, so that at no time will both blades of the propeller be unaccommodated simultaneously. It will be observed that my construction is applicable to all types of aeroplane motors with only insubstantial variations of mounting which will in no way disorder my invention or design generally. In this shield I propose to maintain most of the forced draft of the propeller 2. The

shield 1 graduates into two parallel funnels 3 and 3', seen in Figs. 1 and 2, through which the forced draft is carried horizontally along the top of the motor 10 to the back of my contrivance. It is here that the forced draft enters from both funnels independently, two volute or coiled tubes 4 and 4'. These coil-tubes are so constructed that while one is a right hand, the other is a left hand, screw, 15 both tubes becoming smaller in diameter as the coils, which become smaller spirals, approach the frontal part of the motor. It is manifest that if, while the air is turning to the right in one tube, it is turning to the left in the other tube, the equilibrium of the aeroplane will be assured. I have set my spirals as close together as possible because I have found that only by placing them in this manner may I overcome the irregularities 20 caused on some occasions by a tendency of the wind to blow more strongly from the one side than from the other.

After the air draft has completed its original travel through the coil tubes, it is carried back, through two parallel horizontal tubes 6 and 6', through the core of the coils as illustrated in Figs. 1 and 2. These tubes train this return draft down and under the funnels 3 and 3' and back into their bases in such manner as to divert the impact of the original draft against the beginning of the coils, thus relieving any reactionary force.

Fig. 6 is a sectional view of the valve 7, which is duplicated by valve 7'. Ordinarily 25 this valve is closed. When the air has made its first circuit of my contrivance, it reenters the coils through these valves only when sufficient pressure has accumulated; and then the valve head, being raised as is seen in Fig. 46, the return draft, on account of the direction from which it comes, plays upon the original forced draft in such manner that it relieves any and all reactionary forces, as previously described.

When the air within the vortices becomes greater than will have been found manageable, it finds its escape through the valves 5 and 5'. Fig. 4 illustrates in detail the construction of valve 5. Fig. 5 shows, in sections, valve 5 or 5' closed. The springs 8 and 8' maintain in position the guide pins 9 and 9', attached to the head 11 of the valves. When the vortices have accumulated sufficient pressure to overcome the springs 8 and 8', the 55 valve terminal opens as is shown by dotted line in Fig. 5, thus providing for the reduction of the force. If it is the wish of the pilot to deter the forced draft of the propeller from my contrivance, in order to retard his 60 machine, he may open the vent provided in the back of the wind shield from the cock-pit. Fig. 7 illustrates the details of the construction of this vent.

By simply mounting my opposing coils 65 vertically upon the motor of the aeroplane I

might maintain a regulated reactionary force to the gravitation of the earth.

Having described my invention, what I claim, and what I wish to secure by Letters Patent is:

In aeroplane construction the simple combination of two spiral tubes set either vertically or horizontally atop the motor of said plane, and a shield to catch and train the forced draft of the propeller into said tubes; 70 two tubes to return the forced draft for any further travel within the coil tube.
